CLAIM

The ornamental design for a bolt gripping tool, as shown and described.

DESCRIPTION

FIG. 1 is a perspective view of the top, left end and front of a bolt gripping tool embodying the design;

FIG. 2 is a right side elevational view of the bolt gripping tool shown in FIG. 1;

FIG. 3 is a fragmentary front view thereof, shown with the center section removed for ease of illustration;

FIG. 4 is a fragmentary rear view thereof, shown with the center section removed for ease of illustration;

FIG. 5 is a top view of FIG. 1; and,

FIG. 6 is a bottom view of FIG. 1.

The tool is shown fragmentarily to indicate indeterminate length.

The broken line portion of FIG. 2 is for illustrative purposes only and forms no part of the claimed design.
